UNITED STATES PATENT OFFICE.

GEORGE J. HUNTLEY, OF BALTIMORE, MARYLAND, ASSIGNOR TO THE CROWN CORK & SEAL COMPANY OF BALTIMORE CITY, OF BALTIMORE, MARYLAND, A CORPORATION OF MARYLAND.

PACKAGING APPARATUS.

Application filed November 18, 1921. Serial No. 516,079.

To all whom it may concern:

Be it known that I, GEORGE J. HUNTLEY, a citizen of the United States, residing at Baltimore city, State of Maryland, have 5 invented certain new and useful Improvements in Packaging Apparatus, fully described and represented in the following specification and the accompanying drawings forming a part of the same.

10 This invention relates to improvements in packaging apparatus.

Machines for bottling charged beverages have been devised, in which the bottle is sealed in a head during the filling and capping operation. A cap such as a crown cork is fed to the head, and the cap entrance port then sealed, the crown being held to one side of the head during filling. After filling, the crown is released and is moved 20 to a position over the bottle by a pusher which is carried by the port closer.

It is the principal object of the present invention to provide a packaging apparatus having a port closer and crown pusher that 25 are effective in operation, simple in construction and economical to manufacture.

With this general object in view, the invention consists in the combinations, details of construction and arrangements of parts, 30 which will first be described in connection with the accompanying drawings and then more particularly pointed out.

In the drawings:

Fig. 1 is a view, in side elevation, with 35 parts in vertical section, of part of a packaging apparatus, constructed in accordance with the invention;

Fig. 2 is a vertical cross-sectional view (enlarged) of the packaging head and port closer, showing the latter in open position;

40 Fig. 3 is a similar view showing the port closer closed, with the crown held back for filling;

Fig. 4 is a similar view showing the crown advanced by the pusher;

Fig. 5 is a sectional view taken on the line 5-5 of Fig. 3;

Fig. 6 is a sectional view taken on the line 6-6 of Fig. 3, and

50 Fig. 7 is an edge view of the crown platform plate removed.

Referring to the drawings, the apparatus here illustrated as an example includes a stationary standard 11 having a bearing bracket 12 in which reciprocates a pack-

aging head designated generally by 13. This head may be reciprocated to and from the suitably supported bottles 14, in any preferred manner. The head illustrated as an example, includes a throat ring or capping die 15 such as is well known in the art, a sealing gasket 16, a filling nozzle 17 and a capping plunger 18. Below the capping die is a crown chamber 19 and a crown platform plate 20. To admit crowns 60 to the chamber, the latter communicates with a crown entrance port and passage 21 formed in the head.

In the machine here shown, the head reciprocates and receives crowns from a stationary chute 22 suspended from bracket 12 by a connection 23 and leading from a source of crown supply (not shown). As the head reciprocates the end of the chute bears on a plate 24 forming part of the 70 head. This plate blocks off the chute mouth except when the chute registers with the crown entrance port at the top of the head's stroke, as illustrated in Fig. 2. In this position of the parts a crown *c* can enter the 75 head as shown.

Means is provided for temporarily holding the delivered crown to one side of the crown chamber so as not to interfere with the filling operation. Although this may 80 be accomplished in various ways, as here shown as an example, the filling nozzle 17 normally extends through the crown chamber, as appears in Figs. 2 and 3 and acts as a stop to hold back the crown. After 85 filling, the nozzle is withdrawn to permit complete entrance of the crown as herein-after described. This movement of the nozzle may be accomplished by any suitable mechanism.

There is provided means for sealing the crown entrance port and in structures embodying the invention to the best advantage, a port closer is pivotally connected to the head and is swung into closing position upon the movement of the head toward the bottle. Although capable of various constructions, in that here shown as an example, pivoted as at 26 to the lower part of the head to swing upwardly, is a cylindrical port closer 27 carrying a sealing gasket 28. The other end of member 27 is closed by a cap 29 which is threaded on for convenience in assembly and disassembly. Pivoted to ears 30 on the closer 105 110

member 27 are the arms of a yoke 31 which are formed with slots 32. These slots ride on pins 33 carried by the head. The yoke 31 is pivotally connected with a bar 34 which 5 extends into a casing 35 and is provided with a collar 36. Between this collar and a plug 37 in the casing 35 is a spring 38.

As the packaging head descends, the pins 33 riding down the slots 32 cause the port 10 closer 27 to swing upwardly from the position of Fig. 2 to the position of Figs. 3 and 4. Near the end of the head's downward stroke the bar 34 is pulled down to 15 compress spring 38, thus providing the pressure to hold the port closer with its gasket pressed firmly against the head, sealing the crown entrance port.

Certain features of the packaging head and the port closer means above described, 20 are disclosed and claimed in a copending application Serial No. 468,233.

The invention in its entirety includes a pusher finger pivotally movable with respect to the port closer, a spring carried 25 by the port closer and a connection between the spring and the pusher finger for normally holding the latter in a position for entering the port and for permitting it to remain under the force of the spring while 30 swinging on its pivot. While this may be accomplished in various ways, in structures embodying the invention to the best advantage, the pusher finger is pivotally mounted in a slide movable in the carrier 35 and a tiltable spring-head engages a contact member on or carried by the pusher finger. Although capable of various constructions, as here shown as an example, there is provided a slide 41 comprising a 40 cylindrical portion 42 and a head portion 43. The cylindrical portion 42 is slidable in the body of the port closer 27. The head 43 serves as a bearing for a pivotal pin 44 on which is mounted a pusher finger 45, the 45 pin 44 being parallel to the pivot of the port closer. The free end of the pusher finger is formed with a notch 46 for engaging the skirt of a crown. To prevent turning of the pusher finger, it is, in the 50 present embodiment, rectangular in cross section and extends through a rectangular opening in the front wall of the port closer, as appears in Fig. 6. Enclosed within the body of the port closer and partly within 55 the cylindrical portion 42 of the slide 41, is a coiled spring 47. One end of this spring bears against the cap 29 of the port closer, the other end against a tiltable spring-head 48. As here shown, this spring head 60 is a circular disk loosely inserted in the cylindrical portion 42 of the slide. This spring-head 48 engages a contact lug 49 formed, in the present embodiment, as a heel on the end of the pusher finger. This 65 lug is so located with respect to the pivot

44 that the spring tends to swing the free end of the pusher finger towards the pivot of the port closer, that is, downwardly in the present arrangement. To limit this pivotal movement, the pusher finger is provided with a stop lug 50, for engagement by the spring head 48. 70

In structures embodying the invention in its entirety, the packaging head is provided with a guiding surface for the pusher finger, and in constructions embodying the invention to the best advantage, the pusher finger is held against this guiding surface by the force of the operating spring. Although capable of various constructions, as 80 here shown as an example, the crown platform plate 20 is grooved as at 51, and alining with this groove, is a similar groove in that portion of the head that serves as a bottom wall of the crown entrance passage. 85 The bottom of this combined groove serves as a guide surface against which the finger is held by the spring 42 as the finger moves.

In operation, when the packaging head is elevated to the position of Fig. 2, the port closer is open and down, with the slide 41 pushed forward as far as it will go, by spring 47. The notched end of the pusher finger being free, the finger is swung on its pivot due to the force of the spring on lug 49, until stopped by the engagement of the stop lug 50 with spring-head 48. In this same position of the packaging head, the crown entrance port is in a position to receive a crown *c* which is held back by the lowered nozzle 17. As the packaging head descends, the port closer is swung up on its pivot as above described. This brings the pusher finger in contact with the held crown, the notch 46 engaging the skirt of 105 the crown. Upon continued movement of the port closer the slide 41 is forced back in the port closer, compressing spring 47, the pusher finger swinging on its pivot and the spring-head 48 tilting to some such position 110 as shown in Fig. 3. This Fig. 3 shows the crown port sealed with the compressed spring, through the engagement of the spring-head 48 with lug 49, pressing the crown against the nozzle. 115

After filling, the nozzle is raised as above described. The crown stop being thus removed, the spring 47 is free to expand and the pusher finger is forced through the passage to push the crown into capping position in the crown chamber (Fig. 4). During this movement, as the force of the spring is directed against the lug 49, the pusher finger is held in contact with the guiding surface formed by the groove 51. 120

After the crown has been sealed and crimped on the bottle by means of the plunger 18 and capping die 15 in the manner known in the art, the packaging head is again raised. This causes the port closer 130

to be swung out and down again. As soon as the crown engaging end of the pusher finger is free of the packaging head, it is swung back on its pivot by the pressure of 5 the spring on lug 49, lug 50 controlling the normal position.

What is claimed is:

1. In a packaging apparatus, and in combination, a packaging head having a crown chamber and a crown entrance port and passage, means for temporarily holding a crown to one side of the chamber, a port closer having a pivotal movement with respect to the head, a crown pusher finger carried by the port closer and having a pivotal movement with respect thereto, a spring carried by the port closer for operating the pusher finger to push the held crown, when released, into the chamber, 10 and a connection between the spring and the pusher finger whereby the crown engaging end of the pusher finger is forced toward the pivot of the port closer.
2. In a packaging apparatus, and in combination, a packaging head having a crown chamber and a crown entrance port and passage, means for temporarily holding a crown to one side of the chamber, a port closer having a pivotal movement with respect to the head, a crown pusher finger carried by the port closer and having a pivotal movement with respect thereto, a spring carried by the port closer for operating the pusher finger to push the held crown, when released, into the chamber, 15 and a connection between the spring and the pusher finger for normally holding the latter in a position for entering said port and for permitting the pusher finger to remain under the force of said spring while swinging on its pivot.
3. In a packaging apparatus, and in combination, a packaging head having a crown chamber and a crown entrance port and passage, said passage having a guiding surface associated therewith, means for temporarily holding a crown to one side of the chamber, a port closer having a pivotal movement with respect to the head, a crown 20 pusher finger carried by the port closer and having a pivotal movement with respect thereto, a spring carried by the port closer for operating the pusher finger to push the held crown, when released, into the chamber, and a connection between the spring and pusher finger for normally holding the latter in a position for entering said port, and for holding the pusher finger in engagement with said guiding surface as the finger 25 is moved through the passage.
4. In a packaging apparatus, and in combination, a packaging head having a crown chamber and a crown entrance port and passage and having a guiding surface associated with said passage, means for temporarily holding a crown to one side of the chamber, a port closer movable to close the entrance port, a pusher finger carried by the port closer and pivotally movable with respect thereto, a spring carried by the port closer, and a connection between the spring and the pusher finger whereby the finger is moved by the spring to push the held crown, when released, into the chamber and is held in contact with the guiding surface during said movement.
5. In a packaging apparatus, and in combination, a packaging head having a crown entrance port and passage, a port closer movable angularly into closing position, a slide carried by the port closer, a crown pusher finger pivotally mounted in said slide, and a spring for operating the pusher finger.
6. In a packaging apparatus, and in combination, a packaging head having a crown entrance port and passage, a port closer movable angularly into closing position, a slide carried by the port closer, a crown pusher finger pivotally mounted in said slide, a spring for operating the pusher finger, and an operating connection between said spring and the pusher finger capacitated to accommodate the pivotal movements of the pusher.
7. In a packaging apparatus, and in combination, a packaging head having a crown entrance port and passage and having a guiding surface associated with the port and passage, a port closer movable angularly into closing position, a slide carried by the port closer, a crown pusher finger pivotally mounted in said slide, a spring for operating the pusher finger, and a connection between the pusher finger and spring for normally holding the end of the pusher finger in a position to be received by the port and for holding the pusher finger in contact with the guiding surface as the pusher moves through the passage.
8. In a packaging apparatus, and in combination, a packaging head having a crown entrance port and passage, a port closer movable angularly into closing position, a slide carried by the port closer, a crown pusher finger pivotally mounted in said slide, a spring for operating the pusher finger, and a tiltable head in the port closer between the pusher finger and the spring, with which the pusher finger makes contact.
9. In a packaging apparatus, and in combination, a packaging head having a crown entrance port and passage, a port closer movable angularly into closing position, a slide carried by the port closer, a crown pusher finger pivotally mounted in said slide, and a spring for operating the pusher finger, the pusher finger terminating in a notch for engaging the skirt of a crown.
10. In a packaging apparatus, and in combination, a packaging head having a crown entrance port and passage, a port closer movable angularly into closing position, a slide carried by the port closer, a crown pusher finger pivotally mounted in said slide, and a spring for operating the pusher finger, the pusher finger terminating in a notch for engaging the skirt of a crown.

- 1 combination, a packaging head having a crown entrance port and passage, a port closer movable angularly into closing position, a slide comprising a cylindrical portion and a head portion, a spring, a crown pusher finger pivoted in the head portion of the slide, and a spring-head tiltable in the cylindrical portion of the slide and engaged by the pusher finger.
- 10 11. In a packaging apparatus, and in combination, a packaging head having a crown entrance port and passage, a port closer movable angularly into closing position, a slide movable in the port closer, a crown pusher finger pivotally mounted in the slide and having a plurality of contact portions, a spring for operating the pusher finger, and a tiltable spring-head between the spring and the contact portions of the pusher finger.
- 15 12. In a packaging apparatus, and in combination, a packaging head having a crown chamber and a crown entrance port and passage, means for temporarily holding a crown to one side of the chamber, a port closer having a pivotal movement with respect to the head, a slide in said port closer, a crown pusher finger pivotally mounted in said slide, a spring carried by the port closer for operating the pusher finger to push the held crown, when released, into the chamber, a tiltable spring-head between the spring and the pusher finger, and a contact member on said pusher finger for engagement with the spring head, so located that the spring tends to swing the pusher finger on its pivot.
- 20 13. In a packaging apparatus, and in combination, a movable packaging head having a crown entrance port and passage, a port closer pivoted to said head, means for causing said port closer to swing on its pivot as the head moves, a slide movable in the
- 25 port closer, and comprising a head portion and a cylindrical portion which has a sliding fit in the port closer, a tiltable spring-head within the cylindrical portion of the slide, a spring confined between said spring head and the outer end of the port closer, and two contact members on the pusher finger for engagement with the spring head, one being located so that the force of the spring tends to swing the pusher finger on its pivot, the other being located to act as a stop for limiting such pivotal movement.
- 30 14. In a packaging apparatus, and in combination, a movable packaging head having a crown chamber and a crown entrance port and passage, means for temporarily holding a crown to one side of the chamber, a port closer pivoted to the head to swing in an up and down direction, means for causing the port closer to swing as the head moves, a slide movably mounted in the port closer and comprising a cylindrical portion having a sliding fit within the port closer and a head portion, a tiltable spring-head comprising a loosely located disk within the cylindrical portion of the slide, a spring confined between said disk and part of the port closer, a crown pusher finger for pushing the crown, when released, into said chamber and pivotally mounted in the head portion of the slide, the pivot being substantially parallel to the pivot of the port closer, a contact lug on the pusher finger, located above the pivot of the latter for engagement with the spring head, and a contact lug on the pusher finger located below the pivot of the latter for engagement with the spring head to serve as a stop means to limit the pivotal movement of the pusher finger.
- 35 15. In testimony whereof, I have hereunto set my hand.

GEORGE J. HUNTLEY.
